US00D868530S

(12) **United States Design Patent** (10) Patent No.: **US D868,530 S**
(45) Date of Patent: ** Dec. 3, 2019

(54) **GRINDER**

(71) Applicant: **SHENZHEN WEIKASHI TECHNOLOGY CO., LTD.**, Shenzhen, Guangdong (CN)

(72) Inventor: **Xinshu Zhan**, Guangdong (CN)

(73) Assignee: **SHENZHEN WEIKASHI TECHNOLOGY CO., LTD.**, Shenzhen (CN)

(**) Term: **15 Years**

(21) Appl. No.: **29/650,623**

(22) Filed: **Jun. 8, 2018**

(51) LOC (12) Cl. **31-00**
(52) U.S. Cl. **USPC D7/372**

CLAIM

The ornamental design for a grinder, as shown and described.

DESCRIPTION

FIG. 1 is a top, front and left side perspective view of a grinder showing my new design;
FIG. 2 is a front elevational view thereof;
FIG. 3 is a rear elevational view thereof;
FIG. 4 is a left side view thereof;
FIG. 5 is a right side view thereof;
FIG. 6 is a top plan view thereof;
FIG. 7 is a bottom plan view thereof;
FIG. 8 is an enlarged view of portion 8 in FIG. 2; and,
FIG. 9 is an enlarged view of portion 9 in FIG. 2.
